LOCK FOR PRINTERS' QUOINS

Annibale Fileppo, Brooklyn, N. Y.

Application March 14, 1933, Serial No. 660,625

5 Claims. (Cl. 254—42)

This invention relates to new and useful improvements in locks for printers' quoins.

In the printing trade, it is customary to use quoins for wedging printing matters, such as types and plates or the like in the chase for printing purposes. These quoins generally comprise a pair of opposed wedge shaped members of substantially right angle triangular form, arranged with the hypotenuses in sliding relation 10 with each other and the altitudes parallel to each other and said altitudes being adapted to be parallel in all sliding positions of the members. Frictional resistance is generally used to hold these members in wedged position. In practice, 15 it has been found that very often these members become loose, which is undesirable in several respects, mainly, in that, then the clamped matter is loose and furthermore, there is the possibility that the quoin members may drop out and into 20 the printing machinery with consequent damage to the machinery.

This invention has for an object the provision of a novel arrangement for locking the quoin members in their wedged positions.

Still further, the invention particularly proposes the provision of a resilient member mounted upon one of the quoin members and adapted to engage the teeth of a rack mounted upon the other quoin member in a manner so that the 25 30 quoin members are free to move to accomplish wedging and are restrained from moving in the releasing direction.

Still further the invention contemplates the provision of a novel arrangement whereby the 35 resilient member may be moved to an inoperative position so as to allow the quoin members to move into releasing positions.

As a still further object of this invention, it is proposed to arrange an eccentric member transversely underneath the resilient member and adapted to move the resilient member into the inoperative position previously mentioned whenever desired.

Still further, the invention contemplates an adjustment whereby the quoin members may be held in positions intermediate the lead between the teeth of the rack.

As another object of this invention, it is proposed to slidably mount the rack upon the quoin member and to provide an arrangement whereby the rack may be held in various adjusted positions within limits corresponding to substantially the distance between adjacent teeth of said rack member.

Still further it is proposed to clamp the rack

in the positions mentioned by reason of an eccentric member extended over one end of the rack and adapted to assume a clamping position.

As another one of the objects of this invention, it is proposed to construct a device as mentioned 60 which is simple and durable and which may be manufactured and sold at a reasonable cost.

For further comprehension of the invention, and of the objects and advantages thereof, reference will be had to the following description 65 and accompanying drawing, and to the appended claims in which the various novel features of the invention are more particularly set forth.

In the accompanying drawing forming a material part of this disclosure:—

Fig. 1 is a side elevational view of a pair of quoin members constructed according to this invention.

Fig. 2 is an elevational view of one of the members seen as though looking in the direction of the 75 line 2—2 of Fig. 1.

Fig. 3 is a plan view of the other members seen as though looking in the direction of the line 3—3 of Fig. 1.

Fig. 4 is an end elevational view looking in 80 the direction of the line 4—4 of Fig. 1.

Fig. 5 is a plan view of Fig. 1 seen as though looking in the direction of the line 5—5 of Fig. 1.

Fig. 6 is a transverse vertical sectional view taken on the line 6—6 of Fig. 1.

Fig. 7 is a fragmentary longitudinal vertical sectional view taken on the line 7—7 of Fig. 5.

Fig. 8 is a view similar to Fig. 1 but illustrating a modified arrangement.

Fig. 9 is a sectional view taken on the line 90 9—9 of Fig. 8.

Fig. 10 is a longitudinal sectional view taken on the line 10—10 of Fig. 9.

Fig. 11 is a similar view to Fig. 7 but illustrating 95 a modified arrangement.

The printers' quoins according to this invention comprises a pair of twin quoin members 10 and 11 adapted to coact with each other for wedging purposes as is generally used. Each of these quoin members are substantially of right angle triangular form and are arranged so that their hypotenuses are in contact with each other and their altitudes constitute the parallel surfaces adapted to engage in between the side of the chase 100 and the printing matter.

An arrangement is provided for limiting relative movements of the quoin members 10 and 11 to longitudinal sliding and comprises a central rib 12 upon the quoin member 11 slidably engaged through a central slot 13 in the base of the quoin 110

member 11 and a central rib 14 on the quoin member 11, engaging through a central longitudinal slot 15 upon the base portion of the quoin member 10. Interior opposed faces are formed upon 5 one of the sides of the quoin members 10 and 11, which have teeth 16 adapted to be engaged by the customary clamping tool so that the quoin members may be forced in opposite directions as desired. So far, the construction of the printers' 10 quoins is identical to those quoin members generally used.

The quoin members now depart from the general construction in the provision of ratchet teeth 17 arranged upon one of the ribs, as illustrated on 15 the drawing on the rib 14 and engageable by a resilient member 18 mounted upon the other of the quoin members. The ratchet teeth 17 are arranged longitudinally along the length of the quoin member 11. The resilient member 18 is in 20 the form of a spring and is disposed within a groove 19 extended partially across the top of the quoin member 11 and down one side. The end 20 of the spring 18 is soldered or in any other manner attached upon the quoin member 10. The 25 tip end 21 of the resilient spring 18 is adapted to engage the ratchet teeth 17 so as to hold the quoin members in wedging positions. The teeth 17 are so arranged so as to coact with the end 21 of the resilient member so as to allow the 30 quoin members to be moved in a direction in which the parallel clamping sides move apart to restrain motion in the other direction. A means is provided for holding the resilient element 18 in an inoperative position when desired. This is necessary 35 so as to allow the release of the quoin members after they serve their clamping purposes.

The means mentioned at the end of the previous paragraph comprise a spindle 23 rotatively engaged through the base end of the quoin member 10 and having a central eccentric portion 24 disposed immediately below the resilient member 18. One end of the spindle 23 is provided with a head 25 which is disposed in a recess 26 formed in the side of the quoin member 10. The spindle 45 23 is adapted to frictionally hold any rotative position in which it is placed. The arrangement is such that when the head portion 25 is disposed longitudinally then the cam portion 24 is similarly disposed and the resilient member 18 is 50 free to coact with the teeth of the rack but when the head element 25 is rotated 90° so as to extend downwards, then the extended portion 24 extends upwards and lifts the resilient member 18 slightly so that its free end 21 cannot engage the 55 teeth of the rack.

In Figs. 8, 9 and 10, a modified construction has been disclosed in which an arrangement is provided for adjusting the printers' quoins so that the twin quoin members may assume adjusted 60 positions between the distance of adjacent teeth of the rack. Considering the printers' quoins, it will be realized that the quoin members can be latched only in steps depending upon the distances 65 between the teeth of the rack. In this form, an arrangement is made for adjusting the position of the rack so that intermediate clamping of the quoin members is possible.

More particularly, the quoin members are identical to those previously described except in that 70 a rack 14' has been provided so as to have a dove-tailed base 28 slidably engaging in a longitudinal dove-tailed groove in the quoin member 11 so that the rack may move longitudinally. A rivet 75 29 engages through the quoin member 11 and through an elongated slot 30 in the rack 14' so as

to limit sliding of the rack to substantially the distance between adjacent teeth of the rack. A transverse spindle 31 is mounted through the base end of the quoin member 11 and is formed with an eccentric portion 32 adapted to engage 80 against the upper side of one end of the rack 14' so as to clamp this side downwards and frictionally lock the rack in adjusted positions. To facilitate this locking arrangement serrations 33 are arranged on opposed faces of the rack 14' and the base of the dove-tailed groove in which the rack 14' slides. A head 34 is formed upon one end of the spindle 31 and is disposed within a recess 35, see Fig. 8, formed in the side of the quoin member 11. 85

Normally the quoin members are used as ordinary quoin members except that the head 25 is moved into the horizontal position when the quoin members are engaged in a chase and separated so as to clamp the printing material in the chase. The necessary turning tool is engaged between the teeth 16 so as to very tightly clamp the quoin members in position. To release the quoin members it is necessary that the handle 25 be moved to lift the free end 21 of the resilient member. 90

In the event that it is found that additional tightening of the quoin members is necessary but this additional tightening is less than the distance between adjacent teeth of the rack, it is necessary that the quoin members be removed and the rack 105 14' be adjusted. This latter adjustment is possible by moving the handle 34 so that the clamp portion 32 releases the rack 14'. After the rack has been set in a new position, the handle 34 should be moved back into its clamping position. 110

In Fig. 11, the eccentric portion 24' of spindle 23' is shown to be a flattened surface of the spindle.

It is to be understood that the quoin members and the ratchet teeth of rib 14 may be of any 115 suitable material, such as metal, composition, etc.

While I have shown and described the preferred embodiment of my invention, it is to be understood that I do not limit myself to the precise construction herein disclosed and the right 120 is reserved to all changes and modifications coming within the scope of the invention as defined in the appended claims.

Having thus described my invention, what I claim as new, and desire to secure by United 125 States Letters Patent is:—

1. A lock for printers' quoins, comprising twin quoin members adapted to coact with each other for wedging purposes, a ratchet rack mounted longitudinally on one of said quoin members, a 130 resilient member on the other of said quoin members adapted to engage the teeth of said rack as said quoin members are moved into the wedging positions, and means for holding said resilient member in an inoperative position when desired, 135 said resilient member comprising a leaf spring engaged in a longitudinal groove in the top and one end of one of said quoin members and arranged so that the inturned end engages against the teeth of said rack and said means for holding said 140 resilient member including a controlling transverse spindle rotative on the quoin member having the resilient member and having an offset head disposed in a recess on the top side of the quoin member, said spindle having an offset cam 145 member engageable against said leaf spring and being disposed diametrically opposite said offset head.

2. A lock for printers' quoins, comprising twin quoin members adapted to coact with each other 150

for wedging purposes, a ratchet rack mounted longitudinally on one of said quoin members, a resilient member on the other of said quoin members adapted to engage the teeth of said rack as said quoin members are moved into the wedging positions, and means for holding said resilient member in an inoperative position when desired, said rack being slidably mounted, means for limiting sliding of said rack through a distance substantially equal to the lead of the teeth of the rack, and means for holding said rack in various fixed positions within said limits. 5 3. A lock for printers' quoins, comprising twin quoin members adapted to coact with each other for wedging purposes, a ratchet rack mounted longitudinally on one of said quoin members, a resilient member on the other of said quoin members adapted to engage the teeth of said rack as said quoin members are moved into the wedging positions, and means for holding said resilient member in an inoperative position when desired, said rack being slidably mounted, means for limiting sliding of said rack through a distance substantially equal to the lead of the teeth of the rack, and means for holding said rack in various fixed positions within said limits, comprising a spindle engaged through one of the quoin members and having an eccentric portion adapted to engage against the rack and clamp the rack against the quoin member. 10 4. A lock for printers' quoins, comprising twin quoin members adapted to coact with each other for wedging purposes, a ratchet rack mounted longitudinally on one of said quoin members, a resilient member on the other of said quoin members adapted to engage the teeth of said rack as said quoin members are moved into the wedging positions, and means for holding said resilient member in an inoperative position when desired, said resilient member comprising a leaf spring engaged in a longitudinal groove in the top and one end of one of said quoin members and arranged so that the inturned end engages the teeth of said rack, and said means for holding said resilient member including a controlling transverse spindle having diametrically opposite offset portions and rotative on the quoin member having the resilient member, one of said offset portions being disposed, in a recess on the top side of the quoin member and constituting a handle, and the other of said offset portions engaging beneath said leaf spring for disengaging the leaf member when desired. 15 100 105 110 115 120 125 130 135 140 145 150
